UNITED STATES PATENT OFFICE.

JOHN B. ROHRER, OF PHILADELPHIA, PA., ASSIGNOR TO SAMUEL COOPER,
JOHN HALL, AND JOSEPH B. COOPER, OF SAME PLACE.

DESIGN FOR LOUNGE.

Specification forming part of Design No. **8,054**, dated February 9, 1875; application filed November 2, 1874.
[Term of Patent 3½ years.]

CASE C.

To all whom it may concern:

Be it known that I, JOHN B. ROHRER, of Philadelphia, Pennsylvania, have produced or invented a Design for a Lounge, of which the following is a specification:

My design for a lounge is fully shown in the accompanying photographic illustration.

The back of the lounge consists of two curved portions, *a* and *b*, and a straight portion, *c*. The curved portion *a* is plain, but the curved portion *b* has at the top an ornament, *d*, and at the point where it joins the straight portion a foliated ornament, *e*. The straight portion has near its end an ornament, *f*, of the character too clearly shown to need description. The front of the lounge is made

partly curved and partly straight, and both the front and back of the lounge are ornamented with panels and line-work, in a manner clearly shown in the drawing.

I claim—

The design for a lounge having a back with two curves, *a* *b*, intermediate straight portion *c*, and ornamented at *d*, *e*, and *f* by scrolls and foliations, as set forth.

In testimony whereof I have signed my name to this specification in the presence of two subscribing witnesses.

JOHN B. ROHRER.

Witnesses:

HENRY FUDGE,
JOSEPH B. WELSH.
